UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

LINOTYPE-MACHINE.

No. 828,541.

Specification of Letters Patent.

Patented Aug. 14, 1906.

Application filed April 14, 1906. Serial No. 311,724.

To all whom it may concern:

Be it known that I, PHILIP T. DODGE, of Brooklyn, New York city, county of Kings, and State of New York, have invented a new and useful Improvement in Linotype-Machines, of which the following is a specification.

My invention relates to magazines for linotype-machines which hold in reserve the circulating matrices, more particularly matrices having ears at their ends, as represented in Letters Patent of the United States No. 436,531; and the object of the invention is more particularly to produce magazines of limited height which will carry a large number of matrices.

The usual magazines as ordinarily constructed and used in commercial linotypes of the present day consist of parallel plates grooved longitudinally in their inner opposing faces to receive and guide the ears of the matrices, which latter stand end to end in rows, the two ears on one side of each matrix being seated in the same groove or channel.

My improved magazine is constructed with channels arranged in pairs side by side, so that the ear at the lower end of the matrix will ride in one channel and the ear at the opposite end will ride in the adjacent channel, the result being that the accumulated matrices will overlap each other, thus permitting a large number of matrices to be assembled in a short column.

I prefer to arrange the grooves with a lateral inclination, so that the contained matrices will stand vertically, or practically so, in order to facilitate their delivery or discharge into the assembling mechanism.

Referring to the accompanying drawings, Figure 1 is a perspective view of a matrix such as those used in my magazine. Fig. 2 is a longitudinal section through a magazine and the entrance thereto constructed on my plan. Figs. 3, 4, and 5 are cross-sections on the correspondingly-numbered lines in Fig. 2.

Referring to the drawings, A represents the magazine consisting of parallel plates a , secured to intermediate spacing-pieces a' or otherwise connected to maintain their relations. These plates are provided in their inner or proximate faces with longitudinal parallel channels or grooves a^2 and a^3 , arranged in pairs, those of one plate corresponding to those of the opposite plate.

The matrices B consist, as shown, of flat plates having matrix characters b in one edge and also having on each edge at opposite ends the two longitudinal ears or lips b' and b^2 . These ears are commonly of a thickness less than that of the body of the matrix. The grooves are made of such width and arranged in such relation that each matrix entering the upper end of the magazine may have its lower ears guided in the groove a^2 and its upper ears guided in the adjacent groove a^3 , so that as the matrices bearing any given character enter the pair of grooves devoted to that character they descend by gravity and seat themselves side by side in overlapped positions, as shown in the drawings. The grooves are preferably widened or flared, as shown in the drawings, to facilitate the entrance of the matrices. In this class of machines the composed lines of matrices after use in the casting mechanism are delivered through a distributing mechanism to the upper ends of the magazines, this distributing mechanism releasing each matrix directly over its appropriate channel in the magazine. For the purpose of properly guiding the matrices into my magazine after their release by the distributor I provide above the magazine a throat or entrance C, consisting of parallel plates grooved in their inner faces to guide the matrices and direct them into the upper ends of the magazine-channels. This throat has its channels wide at the upper end in order that the matrices may enter freely, there being but one channel in the entrance for each pair of channels in the magazine.

Each of the entrance channels or grooves is reduced gradually in width toward one side, as shown at c' , this reduced portion being just sufficient to permit the free passage of the ears of the descending matrices. This reduced portion is continued downward to a point distant from the magazine less than the length of a matrix. As each matrix descends its ears ride into the contracted portion of the groove or channel, so that the matrix is held to the right, causing its lower ears to enter the channel a^2 before the upper ears escape from the contracted guide above. As soon as the lower end of the matrix has fairly entered into the flaring mouth of the magazine-channel a^2 the upper ears of the matrix escape from the contracted groove c' , and the matrix immediately tips or cant to the left, so

that as its descent is continued its upper ears will pass into the adjacent channel a^3 .

It will be observed that the grooves or channels of the magazine have a lateral inclination—that is to say, an inclination side-wise in relation to the matrices—and that there is a similar inclination of the channels in the throat or entrance C. This inclination insures the travel of the matrices in the proper course and the passage of their ears into the different grooves.

The release of the matrices from the magazine one at a time may be effected by any suitable mechanism. Good results may be obtained by the employment of the device, shown in the drawings, consisting of a dog or escapement D, mounted to turn around a horizontal pivot d, connected by a rod d' with the keyboard mechanism. This dog being quickly oscillated will release the lowest matrix, permit its escape, and return to its original position in time to arrest the succeeding matrix.

It is to be noted that that portion of the magazine-plate which lies between the two grooves or channels of the pair forms, in effect, a projection which enters between the two ears of the matrices. In other words, the matrix embraces or straddles the projecting portion between its ears. It is manifest that the distance between the grooves and the width of the grooves may be modified at will, so that the assembled matrices resting side by side may depart more or less from the vertical position.

Having described my invention, what I claim is—

1. In a linotype-machine, matrices having ears at their ends in combination with a magazine having channels arranged in pairs to receive the respective matrix-ears.

2. A channeled magazine in combination with matrices having ears at their ends, the ears at opposite ends arranged to enter different channels.

3. A magazine having channels in pairs in combination with matrices having at one end ears to enter one of the channels and at the opposite end ears to enter the other channel.

4. A channeled magazine in combination with matrices having ears at their opposite ends and seated in different channels, whereby the storage of the matrices side to side is permitted.

5. A channeled magazine in combination with matrices each having ears at opposite ends, and means for guiding the respective ears in different channels.

6. The magazine having the inclined channels arranged in pairs, in combination with matrices having ears adapted to enter the two channels, whereby the matrices may be maintained side to side in upright position.

7. In combination with the magazine having channels arranged in pairs, as described, to receive ears at opposite ends of the matrices, the throat or entrance C, having entrance-channels reduced in width, as shown at c'.

8. In combination with the magazine having the channels arranged in pairs, the throat or entrance C, having above each pair of magazine-channels a single entrance-channel reduced in width, as shown at c', and widened below the reduced portion, as shown.

In testimony whereof I hereunto set my hand, this 3d day of April, 1906, in the presence of two attesting witnesses.

PHILIP T. DODGE.
